INVENTORS:

HENRY W. MUHLEISEN,

BY

Graham & Parry H. J. ATTORNEYS.

UNITED STATES PATENT OFFICE.

HENRY W. MUHLEISEN, OF LOS ANGELES, CALIFORNIA, ASSIGNOR TO W. S. RUSH & CO., OF LOS ANGELES, CALIFORNIA, A PARTNERSHIP CONSISTING OF W. S. RUSH, E. S. RUSH, AND B. C. GRAVES.

TIMER.

Application filed February 7, 1921. Serial No. 443,067.

To all whom it may concern:

Be it known that I, HENRY W. MUHLEISEN, a citizen of the United States, residing at Los Angeles, in the county of Los Angeles, and State of California, have invented new and useful Improvements in Timers, of which the following is a specification.

My invention relates to a timer or com-
10 mutator for use in connection with multi-
cylinder engines.

The object of my invention is to provide a
15 timer of the Ford type that will be simple in
construction and positive in its action.

Another object is to provide a timer with
20 a combined rolling and sliding contact ac-
tion which will keep the contact surfaces
clean and insure perfect electrical connec-
tion between the generator and spark plugs.

With these and other objects in view, my
25 invention consists in the construction, com-
bination and arrangement of parts here-
after described and claimed.

In the accompanying drawings which
25 form a part of this specification,

Fig. 1 is a plan view of a timer, embody-
ing the principles of my invention, with
part of the casing broken away and shown
in section.

Fig. 2 is a view in side elevation of the
30 timer shown in Fig. 1 with parts broken
away and shown in section.

Fig. 3 is a detailed sectional view on the
line 3—3 in Fig. 1, showing the contact
35 roller, its mounting parts and its controlling
spring.

Fig. 4 is a section through the roller and
track.

The timer is of a Ford type and comprises
40 a casing 10 within which is fixed an insulat-
ing ring 11 in which contact plates 12 are
embedded. These contact plates connect
with binding posts 13, the binding posts be-
ing insulated from the casing by bushings

45 14. A cam shaft 15 turns in the center of
the casing. A sleeve 16 having two parallel
radial bearing lugs 17 and 18 formed inte-
gral with it is keyed to the cam shaft with-
in the casing and is held thereon by a nut 19,

50 which screws on the end of the shaft. A
roller arm 20 having a pivot pin 21 at one
end which extends through the bearing lugs
17 and 18 has a pivot screw 22 fixed in its
free end upon which a flanged roller 23 is

mounted, the head 24 of the pivot screw serv-
ing to hold the roller in place. As shown in
Fig. 2, roller 23 is adapted to travel inside
the insulating ring 11 and contact with con-
tact plates 12. It has an end flange 25
adapted to press against the inner edge 26
of the insulating ring 11. A retractile coil
spring 27 having one end fixed in bearing
lug 17 and the other in the pivot pin 21
serves the double purpose of holding the
roller 23 against the insulating ring 11 and
contact plates 12 by its unwinding tension
and holding the flange 25 against the edges
of the insulating ring 11 and contact plates
12 by its retractile tension, the latter acting
to withdraw pivot pin 21 from bearing lugs
17 and 18.

Operation: As the cam shaft 15 turns in
the direction indicated by the arrow *a*, the
sleeve 16 and bearing lugs 17 and 18 formed
integral therewith are carried around with
it. The roller arm 20 pivoted in lugs 17 and
18 and the roller 23 attached thereto are thus
caused to revolve around the cam shaft.
The spring acts through the roller arm to
press the roller against the inner periphery
of the insulating ring 11 and the contact
80 plates 12, in the direction indicated by
arrow *b*, by its unwinding tension and at the
same time acts to press the roller flange 25
against the inner edges of the insulating
ring 11 and contact plates 12 in the direc-
85 tion indicated by arrow *c* by its retractile
tension. A rolling contact is thus produced
between the roller and plate faces while a
combined rolling and sliding contact is pro-
duced between the roller flange and the
90 edges of the contact plates. This combined
rolling and sliding contact insures a bright
contact surface and a consequent reliable
electrical connection.

95 While I have shown the preferred con-
struction of my timer as now known to me,
it will be understood that various changes
in the construction, combination and ar-
rangement of parts may be made by those
100 skilled in the art without departing from the
spirit of my invention as claimed.

I claim as my invention:

1. A timer, comprising a casing; an insu-
lating ring fixed in the casing; contact
105 plates embedded in the insulating ring;
binding posts connected to the contact
plates; a cam shaft rotatably mounted

- through the center of the casing; a sleeve keyed upon the cam shaft within the casing; two radial bearing lugs extending from the sleeve; a roller arm fitting against the outer face of one lug; a pivot pin extending from the roller arm through the lugs; a roller carried by the roller arm and adapted to travel inside of the insulating ring and engage the contact plates, and having an end flange adapted to press against the inner edge of the insulating ring; and a coil spring mounted upon the pivot pin between the bearing lugs, one end of the spring being connected to a lug and the other end of the spring being connected to the pivot pin, the tension of the spring being exerted to hold the roller against the insulating ring and contact plates and to hold the flange against the edges of the insulating ring and contact plates.
2. In a timer, the combination of: conducting sections insulated from each other and cooperating to form an annular track; members rotating inside and about the axis of said track; a roller carried on said members; a flange on said roller; and means for holding the periphery of said roller against the inner surface of said track and the flange of said roller against the edge of said track.
3. In a timer, the combination of: conducting sections insulated from each other and cooperating to form a track; members rotating about the axis of said track; a flanged roller; and means for so mounting said roller on said members that it can move radially to cause its periphery to contact with the inside of said track and axially to cause its flange to contact with the side of said track.
4. In a timer, the combination of: contacts having homologous points in a common circle; members rotating about the axis of said circle; a cylindrical roller inside said circle having a flange; and means for so mounting said roller on said members that it moves radially to make contact on its cylindrical surface with said contacts and along its own axis to make electrical contact on its flange with said contacts.
5. In a timer, the combination of: contacts having homologous points in a common circle; members rotating about the axis of said circle; a cylindrical roller inside said circle having a flange, said roller being formed to conform to the shape of said contacts so that the cylindrical portion thereof and the flange can simultaneously make a line contact throughout their width with said contacts; a spindle upon which said roller turns; an arm to the outer end of which said spindle is secured, said arm being pivoted in said members; and a spring forcing the outer end of said arm towards said circle.
6. In a timer, the combination of: a track having electrically conducting sections; a flanged roller adapted to run on said track, said roller being formed to conform to the shape of said track so that the cylindrical portion thereof and the flange can simultaneously make a line contact throughout their width with said track; and means for forcing said flanged roller against said track.

In testimony whereof, I have hereunto set my hand at Los Angeles, California, this 20th day of January, 1921.

HENRY W. MUHLEISEN.
